UNITED STATES PATENT OFFICE.

ELERT A. HILL, OF LOS ANGELES, CALIFORNIA, ASSIGNOR TO STOP-BURGLAR LOCK COMPANY, OF LOS ANGELES, CALIFORNIA, A CORPORATION OF CALIFORNIA.

HINGED CLOSURE.

Application filed February 14, 1922. Serial No. 536,582.

To all whom it may concern:

Be it known that I, ELERT A. HILL, a citizen of the United States, residing at Los Angeles, in the county of Los Angeles and State of California, have invented new and useful Improvements in Hinged Closures, of which the following is a specification.

This invention relates to a door or closure and particularly pertains to a hinged closure of the type embodying a shiftable pivot and the object of the invention is to provide a door or closure mounted to have both reciprocal and pivotal movement whereby the closure may be moved on a straight path of travel to and from its seated position in an aperture and swung to extend to one side of the aperture when in an open position.

Another object is to provide a hinged door or closure of the above character which is especially applicable for use on the doors of safes, lockers, lock-boxes and the like and is so constructed and arranged that the hinge will be concealed when the door is in its closed position. A further object is to provide a hinge which is particularly applicable for use in hingedly mounting circular doors, or the like.

With the foregoing objects in view, together with such other objects and advantages as may subsequently appear, this invention consists in the parts, and in the construction, combination and arrangement of parts, or the equivalents thereof, as hereinafter set forth and illustrates by way of example in the accompanying drawings in which:

Figure 1 is a view in elevation of the hinged closure.

Fig. 2 is a view in elevation showing the closure in an open position.

Fig. 3 is a view in horizontal section as seen on the line 3—3 of Fig. 4.

Fig. 4 is a view of the door, a closure as seen in rear elevation as indicated by the dotted line 4—4 in Fig. 3.

Fig. 5 is a detail in section as seen on the line 5—5 of Fig. 4.

More specifically 7 indicates a door or closure which is here shown as circular in form and adapted to close a circular aperture 8 in wall 9, the margin or casing of which aperture is preferably formed of a cylindrical tube 10 here shown as screwed

into engagement with the wall 9 but which 55 may obviously be fastened thereto in any suitable manner.

The outer end of the tubular casing is arranged to extend a short distance outwardly from the outer face of the wall 9 so 60 as to form an annular flange 11 around the margin of the aperture, and the inner face of the door is formed with an annular channel 12 to receive the flange; the outer wall of the channel being formed by an annular flange 13 on the margin of the door and the inner wall of the channel being formed by an annular flange 14 which is designed to closely fit the inner perimeter of the casing 65 10 in slidable engagement therewith when the door is in its closed position. It will be seen that in order to open or close the door that it must be moved in a straight path to dispose the flanges thereon in and out of telescoping engagement with the casing. 70 The present invention contemplates the provision of a mounting for the door whereby it may be given this reciprocal movement and also to afford means whereby the door may be swung on a pivot to extend to one 75 side of the aperture when in its open position, and in carrying out the invention a stem 15 is pivotally mounted on the inner face of the door and slidably engaged with a sleeve 16 on the casing. The stem is here 80 shown as connected to the door by a pivot pin 17 which is carried by a yoke or spaced flanges 18 on the door and on which pin the stem is turnable to form a hinge mounting for the door. The sleeve 16 may be 85 affixed to the casing 10 in any desired manner and the stem is extended therethrough such distance as to afford sufficient slidable movement of the stem that the door may be pulled outward such distance as to dispose 90 the pivot pin forward of the front of the wall so that the door may be swung on the pivot to extend outwardly to one side of the aperture. The stem is fitted with a spring 95 15 which is here shown as wound on the stem and bears between the sleeve 16 and a collar 20 on the stem in such manner as to exert a yieldable longitudinal pressure on the stem 100 tending to close the door.

The door may be equipped with any suitable lock or latch mechanism, but is here shown as fitted with a combination lock of the push button type, the specific construction

of which forms no part of this application and therefor does not need to be described in detail herein.

The operation of the invention is apparent from the foregoing, it being seen that in opening the door it is necessary to pull it outwardly on a straight path to withdraw the flange 14 out of engagement with the casing, and that on pulling the door outwardly, the stem 15 will slide outwardly in the sleeve 16 in opposition to the spring 19 which will yield under the pull to which the door is subjected. On drawing the stem outwardly the pivot pin on the door will be disposed such distance in front of the wall that the door may be swung on the pivot into an open position as shown in Fig. 2. In closing the door it is swung on its pivot to bring the flange 14 directly in front of the casing whereupon the door will be advanced on a straight line to seat the flange 14 in the casing and also seat the flange 11 of the casing in the channel 12 of the door.

I claim:

1. The combination of a door, a casing surrounding an aperture to be closed by said door, a stem slidably mounted on said casing, a pivot connecting the inner portion of said door to said stem, and a spring acting on said stem yieldably opposing movement thereof in one direction.

2. The combination of a door, a casing surrounding an aperture to be closed by said door, a sleeve in said casing, a stem slidably

in said sleeve, a pivot pin connecting the inner portion of said door to said stem, and a spring acting on said stem yieldably opposing outward movement thereof. 35

3. The combination of a casing surrounding an aperture formed with an annular flange around the margin of the aperture, a door adapted to close the aperture having an annular channel on its inner face to receive said flange, a stem pivotally connected to said door and slidably carried on said casing forming a support for the door whereby the latter may be moved on a straight path of travel to and from the casing and also swung to one side thereof. 40

4. The combination of a wall formed with an aperture, a casing arranged in the aperture and projecting forward of the wall to form an annular flange, a door formed with a marginal flange adapted to encircle said casing and abut against the wall, a second flange on said door adapted to extend into said casing in slidable contact therewith, a stem slidably supported in said casing, a pivot pin hingedly connecting said door to said stem, said stem adapted to move outwardly whereby the door may be moved on a straight path of travel in and out of engagement with the casing, and a spring acting on said stem yieldably opposing outward movement thereof normally tending to close the door. 45 50 55 60 65
